DESIGN FOR A LAMP GUARD

Nathan Rodney Schwartz, New York, N. Y.

Application June 23, 1943, Serial No. 110,509

Term of patent 14 years

(Cl. D48—14)

To all whom it may concern:

Be it known that I, Nathan Rodney Schwartz, a citizen of the United States, residing at New York, in the county and State of New York, have invented a new, original, and ornamental Design for a Lamp Guard, of which the following is a specification, reference being had to the accompanying drawing, forming a part thereof.

In the drawing:

I claim:

The ornamental design for a lamp guard, as shown.

NATHAN RODNEY SCHWARTZ.
